UNITED STATES PATENT OFFICE.

ROSWELL L. PEABODY, OF NEW YORK, N. Y.

IMPROVEMENT IN WATCHES.

Specification forming part of Letters Patent No. 34,978, dated April 15, 1862.

To all whom it may concern:

Be it known that I, ROSWELL L. PEABODY, of the city, county, and State of New York, have invented certain new and useful Improvements in the Construction of Watches; and I do hereby declare that the following is a full, clear, and exact description of the same, reference being made to the annexed drawings, making a part of this specification, which are fully described herein, and in which similar letters indicate similar parts throughout the figures.

My invention consists, first, in the manner of imparting motion to the balance from the escapement; secondly, in a manner of securing the hair-spring to the regulator and of constructing the stud in which the fixed or outer end of the hair-spring is held; thirdly, in an improved construction of the staff of the balance, and, fourthly, in a manner of setting the hands.

The first part of my invention is a method of giving a longer arc of vibration to the balance as well as of giving an impulse in each direction.

Figure I is a top or plan view showing the balance and the lever of the escapement, and Fig. II is an elevation showing the same with other parts partly in section.

At *a* is the axis or staff of the balance.

b is the roller, and *c* the lever-arm.

At *d* is a pin rising vertically from the arm *c*, and when that arm is in such position that its pin *d* is in line with the axes *a* and *f* of the balance and the lever the pin should be within the periphery of the roller *b*. To permit this two notches *i* and *i'* are cut in the edge of the roller. The lever-arm terminates in two prongs, as shown in Fig. I, and on the lower side of the roller is a single pin *e*, placed midway between the notches and projecting downward far enough to engage the prongs. The notches in the edge of the roller are to be cut at such distance from each other as will permit the pin on the lever to enter one of them when the pin on the roller, by striking against the inside of that one of the prongs which will be in the line of the axes *a* and *f*, or nearly so, has moved the lever far enough to effect the unlocking of the pallets of the escapement. Hence the distance must be governed by the length of the

head of the lever-arm and that length by the throw of the lever.

The operation of this part will be that when the balance is returning in the direction indicated in Fig. I its pin *e* will on reaching the prong *c'* move the lever to commence a return-throw. The pin *d* on the lever then enters the notch *i*, and as by that time the pallets will have been unlocked this pin then gives the impulse, throwing the balance onward to complete its arc of vibration. On the return of the balance the lever will be at rest on the opposite side at the extent of its throw. The pin *e* will therefore strike the other prong *c''* of the lever and the pin *d* will consequently enter the other notch *i'* of the roller, thus giving an impulse in the opposite direction.

The second part of my invention will be described with reference to Figs. II and III. In this the outer coil of the hair-spring is seen at *g*, the arm of the regulator at *h*, and a stud at *k*. As usually constructed, there are upon the arm *h* two small pins projecting downward, one on each side of and near to the hair-spring, the regulating being effected by moving the arm which carries those pins nearer to or farther from the stud in which the outer end of the spring is secured. As is well known, there is a degree of vibration in that portion of the spring lying between the stud and the pins, and this vibration is to be avoided if extreme accuracy is desired. I prevent it by making, instead of the pins, a permanent and comparatively-broad rest on the arm, as at *m*, the side of which next the spring is to have the proper curve due to the shape of the spring, and placing a broad sliding piece *n* on the arm, the inner end of which is also curved to fit against the spring. This sliding piece is secured in close contact with the hair-spring by a set-screw (seen in dotted line at *n'*) clamping it against the permanent rest *m*, and when the position of the regulator is to be changed the set-screw must be started and the slide moved out a little, to be again set up close when the regulator is in the desired position. The spring is thus held between surfaces which inclose an arc or portion of several degrees of the spring, and hence no motion will take place between this

point and the stud. Instead of the fixed stud, in which it is very difficult to drill the hole so that the hair-spring will not be deflected, out of the proper position due to its curve, I employ a small short cylinder having the proper hole drilled through from side to side and parallel with its ends, to receive the end of the hair-spring and the locking-pin. This cylinder is seen at *k*, Figs. II and III, and separately in Fig. VI, which is an enlarged view in perspective of the cylinder or stud, and is held in place by making a shallow countersink in the "cock" of the balance and placing another smaller cock *o* against the lower end to retain it in position, as clearly shown in Fig. II. The stud is thus free to turn around, so as to adapt itself to the proper position which should be taken by the spring, and when the hair-spring is put in place and the stud has taken its due position it will be retained there by screwing the piece *o* firmly into place. If the upper cock is too thin to admit of being countersunk, as in some kinds of watches it will be, a pin may be made on the upper end of the stud, which pin, inserted into a hole in the cock, will be sufficient to hold the stud in place when *o* is screwed tightly down.

The third part of my invention is an improvement in the manner of constructing the staff of the balance, whereby it may be more readily repaired when a pin is broken, as well as have the several parts which are attached to it more accurately fitted. Heretofore this staff has been a single piece of steel upon which was fitted, first, the balance, above that the "collet," and below the balance the roller. When all of these have been duly adjusted, the pivots on the ends are to be turned off; and as these are very delicate they are frequently broken, particularly if the watch is dropped. To be properly repaired an entire new staff should be put in, though, as is well known to the trade, the repairing is often done with much less work. I construct it by making a short tube of steel, as seen at *p*, Figs. I and II, and this is to have the balance fitted upon it, although I prefer to make it and the balance from one piece of metal. The collet and the roller are then to be fitted on. The bore of the tube

should be slightly tapering, and in this is to be inserted a rod of steel *r*, made to fit closely, upon the ends of which the pivots can then be turned. If one of these become broken the piece *r* may readily be removed, a new one inserted, and pins turned on it, without requiring any new adjustment of the other parts.

The fourth part of my invention is a method of setting the hands whereby I am enabled to make the center shaft solid and yet to set them from the back. I place at one side an additional shaft *s*, Figs. IV and V, which passes through both plates of the watch, and having at the back a square to take on a key, as at *t*, and on the other end a toothed wheel *u*, of such size that it will be capable of gearing into the wheel *v* of the usual train, which reduces the motion from the minute to the hour hand. Thus by turning the shaft *s* the motion will be communicated to the hands.

I claim—

1. The combination of the unlocking-pin *e* with the prongs of the lever, and of the impulse-pin *d* with the notches in the roller, in the manner and for the purposes substantially as set forth.

2. The manner of securing the hair-spring to the regulator by means of the fixed and sliding pieces *m* and *n*, between which it may be firmly clamped, as set forth.

3. The use or employment of the cylindrical and self-adjusting stud *k*, when said stud is secured upon the under side of the cock of the balance, in the manner substantially as set forth.

4. Constructing the staff by making it in two parts, upon one of which the roller, &c., is fitted, and upon the other the pins are turned, for the purposes and in the manner substantially as described.

5. The supplementary shaft *s*, in combination with the gear of the center shaft for setting the hands, as set forth.

In witness whereof I have hereunto subscribed my name.

ROSWELL L. PEABODY.
